REFRIGERANT SYSTEM AND APPARATUS

Chester A. Kuebler and William J. Bolton, Erie,
Pa., assignors to Uniflow Manufacturing Company,
Erie, Pa., a corporation of Pennsylvania

Application February 11, 1937, Serial No. 125,239

4 Claims. (Cl. 62—116)

This invention relates to a mechanical refrigerator and more particularly to an improved refrigerant system for providing cooling zones of different temperatures.

5 It is highly desirable in various types of mechanical refrigerating apparatus that cooling zones of different temperatures be provided. For example, the conventional domestic electric refrigerator comprises a main heat insulated cabinet with a cooling unit therein which is adapted to maintain a freezing temperature within an ice tray compartment and a somewhat higher temperature such as 40° in the cabinet generally. 10 However, when it is desired to effect rapid freezing of ice cubes, the refrigerant pressure in the evaporator is substantially lowered resulting in a sub-freezing temperature in the coils disposed adjacent the external walls of the ice tray compartment and the temperature throughout the main 15 cabinet is often lowered to near the freezing point. This results in the absorption of moisture from articles stored in the cabinet to an undesirable degree, particularly meats and similar articles, and also from the air in the cabinet considerably 20 lowering the humidity with a resultant deposit of frost on the evaporator coils. Under these conditions the humidity will be approximately 25% whereas for the proper preservation of foods it should be at a considerably higher value, such as 65%. Additionally, the coating of frost on the evaporator coils due to the freezing and sub-freezing temperatures acts as an insulating medium resulting in inefficient heat exchange and necessitating frequent defrosting. 25

30 We have devised a refrigerant system adapted to domestic refrigerators wherein the ice tray compartment although disposed in the main cabinet is insulated therefrom, effecting quick formation of ice, the coils associated with the external walls of the ice tray compartment are not subjected to freezing temperatures whereby the temperature of the food storage cabinet generally is not lowered to the freezing point but is maintained at a desired normal operating temperature such as 40° F. Thus, the cooling action during quick freezing of ice tubes is confined substantially entirely to effecting freezing and sub-freezing temperatures within the ice tray compartment only, resulting in low current consumption by the compressor and relatively little moisture is extracted from articles in the main cabinet and from the air within the cabinet. A relatively high humidity such as 65% is thereby maintained in the storage cabinet and since the

coils externally of the ice tray compartment are maintained above freezing temperatures at all times, there is no frost deposit on these coils.

We are familiar with various systems endeavoring to achieve this result by providing two independent systems one controlled by the cabinet temperature and the other by the temperature of the ice cube compartment and also systems of the double transfer type. However, we employ a single, relatively simple, inexpensive system for both the cabinet and the ice tray compartment and quick freezing is effected within the ice tray compartment by manipulation of a manual control valve wherein a relatively lower refrigerant pressure is obtained in the portion of the refrigerant conduit system cooling the ice tray compartment than in the portion of said system cooling the cabinet generally. 5 10 15

The primary object of our invention therefore is to provide a single refrigerant system wherein a refrigerant pressure may be maintained in one portion of the system effecting freezing and sub-freezing temperatures and a relatively higher refrigerant pressure may be obtained in another portion of the system effecting non-freezing temperatures. 20 25

Another object of our invention is to provide a single refrigerant system for refrigerators having relatively heat insulated compartments adapted to be maintained at the same or different temperatures optionally, wherein the temperature of one compartment may be substantially maintained at constant above freezing temperature, and another compartment may be subjected to near-freezing or sub-freezing temperatures upon 30 35 operation of a manual valve.

Another object of our invention is to provide a refrigerant system for domestic refrigerators comprising a main cabinet and a relatively heat insulated ice tray compartment disposed therein and wherein the temperature of the evaporator coils in the main cabinet may be maintained above freezing to prevent frost formation on the coils and the temperature of the ice tray compartment may be manually controlled to alter the rate of freezing without altering the temperature of the main cabinet. 40 45

Another object of our invention is to provide a refrigerator of the above type which is relatively efficient requiring an extremely low current consumption due to short operating time obtained when both coils are operated at high pressure and temperature, making the compressor operation very efficient due to the resulting high back pres- 50 55

sure and providing a relatively high degree of humidity in the main cabinet at all times, even when the freezing compartment coil is operated at sub-freezing temperature.

- 5 Another object of our invention is to provide a domestic refrigerator of the above type which is relatively efficient requiring a low current consumption and which maintains a relatively high degree of humidity in the main cabinet.

- 10 Other objects of our invention and the invention itself will become increasingly apparent from a consideration of the following description and drawings herein:

Fig. 1 is a front elevational view of a domestic refrigerator embodying our invention:

Fig. 2 is a diagrammatic view of the refrigerant system illustrated in Fig. 1:

Fig. 3 is a perspective view of a cooling unit, including an ice tray compartment which we may employ in the refrigerator illustrated in Fig. 1 and with a closure portion removed.

Fig. 4 is a perspective view of a closure portion for the unit of Fig. 3:

Fig. 5 is a longitudinal sectional view of a manual control valve which we may employ in the system of Fig. 2, and

Fig. 6 is a section taken along line 6—6 of Fig. 3.

Referring now to the drawings, we have illus.

30 trating how to the drawings, we have illustrated generally at 10, Fig. 1, a domestic refrigerator of the type generally illustrated in a net-

erator of the type generally illustrated in a patent to C. A. Kuebler, No. 2,064,926 but embodying our improved system. Although for reasons

35 ing our improved system. Although for purpose of illustration, we have shown our system as embodied in a domestic type refrigerator, the

35 embodied in a domestic type refrigerator, it is understood that it is equally adaptable to commercial apparatus of varying types having two relatively insulated compartments maintained at different temperatures wherein it is desired to

40 different temperatures wherein it is desired to rapidly reduce the temperature of one compartment without substantially effecting the temperature in other compartments.

perature in other compartments. The refrigerator 10 comprises the usual compartment 11 in the bottom portion of the refrigerator for housing

45 ing the compressor-condenser unit, a main storage compartment 12 within which is disposed a

cooling unit 13, preferably secured to the top of cabinet 12. Beneath the main storage compartment 12 we may provide an auxiliary compartment

50 **ment 14** adapted to be cooled from the main compartment but the particular construction of

compartment but the particular construction of the refrigerator apart from the refrigerant system, constitutes no essential part of our invention.

55 system, constitutes no essential part of our invention and may take any form desired. The refrigerant system illustrated in Figs. 1 and 2 comprises the usual compressor, condenser, etc.

comprises the usual compressor unit 15 operable by an electric motor 16 whereby refrigerant gas under pressure is supplied to the coil 17.

under pressure will pass from the compressor 15 to the usual condenser unit 17 and will then pass in liquid form through a conducting line 18 to

a float valve 19. The float valve 19 admits liquid refrigerant to a coil 20 having heat conducting

refrigerant to a coil 18 having heat conducting fins generally indicated at 21 associated therewith. The refrigerant will then pass by a line 22 to a manually controllable valve 23 and then

to a manually controllable valve 23 and thence to a coil 24 having an outlet in a header 25 from which the refrigerant is conducted back to the compressor or pump 15 by line 26.

The valve 23 also has a connection with a tube 27 leading to a switch 28 controlling the operation of the compressor motor 16. Although switch 28 is illustrated as being operably responsive to pressure in tube 27, it is understood that a thermally responsive switch may be employed, both types of switches being of well known construction.

struction. Also, a conventional pressure responsive expansion valve may be used in place of the float valve 19, but for operating results we prefer the float type valve.

Referring now to Figs. 3, 4 and 6 illustrating the cooling unit 13, it will be noted that the cooling unit comprises a generally boxed shaped sheet metal housing 30 having out-turned lateral flanges 31-31 whereby the housing may be welded or otherwise suitably secured to the top 10 of the main storage compartment 12. The housing 30 is internally lined at the base, side and rear walls with suitable heat insulating material indicated at 32, the insulating material 32 extending upwardly for a major portion of the 15 housing height. A plurality of sheet metal shelves 33 are supported in spaced relation within the housing 30. The external walls of the housing 30 are provided with a plurality of vertically extending heat conducting fins generally 20 indicated at 21 preferably by securing a corrugated sheet metal strip to the lateral and rear walls of the housing, although the heat exchange area of fins 21 will be dependent upon the heat 25 exchange surface required to properly cool the main compartment 12. The coils 20 are disposed intermediate the fins 21 and refrigerant will flow from float valve 19 through a line 34 to the coils 20 and thence through line 22 projected through a lateral wall of housing 30 to 30 the control valve 23. The refrigerant passes from control valve 23 to coils 24, which are disposed beneath shelves 33 by a line 35. We contemplate it will only be necessary to dispose coils 24 beneath some of the shelves 33 to effect the 35 desired temperature within the ice tray compartment, but this arrangement may be altered as desired and we preferably place a pan immediately beneath the coils as indicated at 36 to prevent frost and the like from being deposited on trays supported on a lower shelf. 40

The door frame indicated at 37 is preferably
held of suitable heat insulated material and
is secured to the front face of housing 30 in any
suitable manner, the frame being provided with
hinged door 38 also heat insulated permitting
access to the interior of housing 30. The top
portion of frame 37 is perforated as indicated
at 39 whereby a control member for switch 28
may be projected therethrough and is also perfo-
rated at 40 whereby a control member for valve
3 may be projected therethrough, thus render-
ing these control members easily accessible for
manual manipulation upon opening the door of
main cabinet 12.

The construction of control valve 23, best illustrated in Fig. 5, will now be described. The valve 23 comprises a generally cylindrical element 41 provided with an enlarged threaded bore 42 extending into a relatively reduced forward portion 43 and terminating in a further reduced co-axially disposed forward portion 44, the forward portion 44 having a generally frusto-conical valve seat 45. Extending from portion 44 is a lateral inlet 46 to which line 22 is sealingly secured and a lateral outlet 47 to which line 35 is sealingly connected. The portion 43 and the lateral inlet 46 are connected by a relatively small by-pass 48 and disposed within portion 43 is a generally cylindrical valve element 49 having a conical tip adapted to engage valve seat 45 and an enlarged shoulder portion 50 ideally engaging the walls of portion 43. A compression spring 51 abuts a shoulder formed 60 65 70 75

intermediate bored portions 43 and 44 and also abuts the shoulder portion 50 of valve element 49 and tends to maintain the valve element spaced from its valve seat. The enlarged shoulder portion 50 of the valve element is recessed to receive the inner end of an axially movable pin 52, the pin 52 being movable by a toggle cam 53. A nut 54 threadedly engages bore 42 of element 41 and is centrally bored to permit the member 52 to be projected therethrough. The enlarged shoulder portion 50 of valve element 49 is sealingly connected to one end of a Sylphon bellows 55 and the opposite bellows end is sealingly connected to the outer portion of bore 43 preventing leakage of refrigerant fluid. The nut 54 is adapted to engage a second nut 56 to grip therebetween peripheral portions of the frame perforation 40 as indicated at 57 to form a secure mounting for the control valve 23.

20 The portion 44 of the element 41 is also provided with a relatively small lateral opening 58 to which the tube 27 leading to switch 28 is connected whereby the pressure of refrigerant in coil 20 and the portion 44 will be communicated to 25 the pressure responsive element controlling switch operation.

The operation of the system will now be described. As previously stated, refrigerant flows from the coils 20 disposed externally of housing 30 30 to the coils 24 disposed internally of the housing and flow into coil 24 is controlled by valve 23. With the handle of the toggle cam 53 in the position illustrated in Fig. 5 the flow of refrigerant from coil 20 to the inlet passage 46 and 35 through outlet passage 47 will be substantially unrestricted and the refrigerant pressure and consequently temperature in both coils 20 and 24 will be substantially the same. Under these conditions, the ice tray compartment would be 40 only slightly cooler than the food compartment generally and since the compressor is caused to operate with refrigerant at relatively high back pressure, it is relatively economical. If the handle of the toggle cam 53 were turned to closed 45 position or downwardly, the movement of pin 52 would cause valve element 49 to close the passage leading to outlet 47. Any refrigerant passing to the outlet 47 would necessarily traverse the small by-pass 48 and this would cause a restriction and 50 result in lowering the pressure at outlet 47 and cause the refrigerant fluid in coil 24 to be evaporated at a lower temperature. Refrigerant fluid in coil 20 would be evaporated more slowly since switch 28 is responsive to the pressure of refrigerant fluid in coil 20 through the connecting tube 27 but the pressure of refrigerant fluid in coil 20 would remain substantially the same since 55 the operation of the compressor pump in starting and stopping would control this pressure.

60 The pressure at which switch 28 cuts the compressor out of operation corresponds to a temperature slightly above freezing such as 35° Fahrenheit so that there is no tendency for frost to accumulate on coils 20 either during normal 65 operation of the refrigerator or when adjusted to effect quick ice formation in the ice tray compartment.

Thus, we have provided a relatively simple and inexpensive system of refrigeration wherein two 70 cooling zones of different temperatures may be maintained and the temperature of each zone may be manually controlled. The temperature of the food compartment generally may be controlled through manipulation of switch 28 operating the compressor and the temperature of the 75

ice tray compartment through the adjustable valve 23.

During periods when the valve 23 is maintained open both coils 20 and 24 will have substantially the same temperature and the compressor will 5 be operating under a relatively high back pressure of refrigerant fluid resulting in economical operation.

Although we have shown and described modifications of our invention, we contemplate that 10 numerous and extensive departures may be made therefrom without departing from the spirit of our invention or the scope of the appended claims. Having thus described our invention, what we claim is:

1. A cooling unit for a refrigerator comprising a generally box-shaped housing adapted to be mounted in the food storage compartment of the refrigerator and having heat insulated walls, evaporator coils secured to the external walls of 20 the housing, heat conducting fins associated with the coils extending outwardly from the housing walls, a plurality of shelves within the housing, evaporator coils disposed within the housing and adjacent the shelves, conduit means projected 25 through the housing walls connecting the externally and internally disposed coils, a manually controllable pressure reducing valve disposed in the conduit means for adjustably reducing the pressure of refrigerant fluid in the internally disposed coils relative to the externally disposed coils, and means associated with said valve 30 adapted to transmit refrigerant pressure in the external coils to a pressure responsive electric switch. 35

2. A cooling unit for a refrigerator comprising a generally box-shaped housing adapted to be mounted in the food storage compartment of the refrigerator and having heat insulated walls, an evaporator coil, secured to the external walls of 40 the housing, a shelf within the housing, evaporator coils disposed within the housing and adjacent the shelf, conduit means connecting the externally and internally disposed coils, a manually controllable pressure reducing valve disposed 45 in the conduit means for adjustably reducing the pressure of refrigerant fluid in the internally disposed coils relative to the externally disposed coils, and means associated with said valve adapted to transmit refrigerant pressure in the external 50 coil to a pressure responsive electric switch.

3. A cooling unit for a refrigerator comprising a generally box-shaped housing adapted to be mounted in the storage compartment of the refrigerator and having heat insulated walls, evaporator coils associated with the external walls of the housing, a shelf within the housing, evaporator coils disposed within the housing and adjacent the shelves, conduit means connecting the externally and internally disposed coils, a manually controllable pressure reducing valve disposed 55 in the conduit means for adjustably reducing pressure of refrigerant fluid in the internally disposed coils relative to the externally disposed coils, and said pressure reducing valve being 60 accessible externally of the housing.

4. A cooling unit for a refrigerator comprising a generally box-shaped housing adapted to be mounted in the storage compartment of the 70 refrigerator and having heat insulated walls, evaporator coils associated with the external walls of the housing, a shelf within the housing, evaporator coils disposed within the housing and adjacent the shelf, conduit means connecting the 75

externally and internally disposed coils, a manually controllable pressure reducing valve disposed in the conduit means for adjustably reducing the pressure of refrigerant fluid in the internally disposed coils relative to the externally disposed coils, a receiving tank for refrigerant fluids, a

pressure responsive electric switch connected with the valve, and a compartment in the upper portion of the housing within which the switch, the valve and the tank are disposed.
